PORTABLE BOWLING ALLEY

Warren A. Somerville, Jackson Heights, N. Y.

Application November 13, 1941, Serial No. 418,922

2 Claims. (Cl. 273—51)

The invention relates to improvements in portable bowling alleys and has for its primary object the provision of an improved construction of simple character which is capable of economical production and highly efficient in use.

Other objects will appear hereinafter.

The invention consists of the combinations and arrangements of parts hereinafter described and claimed.

The invention will be best understood by reference to the accompanying drawing forming a part of this specification and in which

Fig. 1 is a top plan view of a bowling alley embodying the invention;

Fig. 2 is a side view thereof;

Fig. 3 an enlarged side view of one of a plurality of joints employed between the sections of the side members thereof;

Fig. 4 an enlarged detail section taken substantially on line 4—4 of Fig. 1;

Fig. 5 an enlarged sectional detail view taken substantially on line 5—5 of Fig. 1;

Fig. 6 an enlarged detail cross-section taken substantially on line 6—6 of Fig. 1; and

Fig. 7 an enlarged vertical section taken substantially on line 7—7 of Fig. 1.

The embodiment of the invention illustrated in the drawing comprises sectional side members each comprising a side rail portion 10 and a gutter portion 11. These side members are made up of a plurality of sections as shown joined together by dowels 12 and locking links 13 as indicated to make up the complete side members of the alley. Each of the gutter members 11 is provided with a ball groove 14 adapted to receive a bowling ball 15 as indicated and for the usual purpose. As will be noted the different sections of the side members are so arranged that the joints 16 between them are staggered with relation to each other which arrangement materially stiffens and strengthens the construction as will be readily understood.

The bed of the alley is also made up of a plurality of sections 17 arranged to rest in grooves 18 provided in the inner edges of the gutter sections 11 and being held in place by means of dowels 19. The bed members 17 are secured to each other by means of beveled tongues 20 fitting snugly and tightly in correspondingly shaped sockets 21 in securing blocks or heads 22 on the undersides of the sections and whereby a tight and smooth joint is formed between said sections as will be readily understood. As will be noted the joints between the sections 17 are also staggered with relation to the joints between the side members thus further stiffening the construction.

A ball return chute 27 is pivoted as shown to a post 28 which is secured to one of the side members, said chute being pivoted at a sufficient height to permit of the free passage of balls thereunder

as indicated by the dotted lines in Fig. 2. The chute 27 is so balanced on its pivot that it will normally rest against a stop pin 29 on the post 28 and thus be held in a slightly inclined position as indicated by the dotted lines in Fig. 2. When a ball is deposited on said chute, the same will roll to the forward end thereof thus overbalancing the same and causing the forward end to swing downwardly to register with the corresponding groove 14, thereby returning the ball to the bowler. As soon as the weight of the ball is thus removed from the chute 27, it will automatically swing back to its normal unoperative position through the force of gravity and the fact that the same is unbalanced on its pivot. In this way the chute is normally held out of danger of injury from balls running off of the alley but will serve to return the balls to the bowler as will be readily understood.

20 A stop post 30 is arranged at the front end of the gutter member thus receiving the balls for return and the sponge rubber cushion 31 is provided on said stop post to cushion the return of the balls. By this arrangement a simple and efficient portable alley is provided which is capable of economical protection and highly efficient in use. The specific form and arrangement parts disclosed is a simple and effective one for the purpose.

25 While I have illustrated and described the preferred form of construction for carrying the invention into effect, this is capable of variation and modification without departing from the spirit of the invention. I therefore do not wish to be limited to the precise details disclosed but desire to avail myself of such variation and modification as falls within the scope of the appended claims.

I claim:

30 1. A bowling alley comprising two longitudinal side members made up in detachable sections, each section consisting of a vertically extending side rail having an inwardly extending ball gutter portion at the bottom thereof, said sections being 45 detachably connected to each other at their ends by dowels and also by locking links which span the joints between them, the joints between said sections being arranged out of transverse registration with each other; and a sectional alley bed 50 member detachably secured to said gutter portions by dowels, said bed sections being provided at the under sides of one of their ends with longitudinally projecting tongues, the other ends being provided with sockets to receive said tongues.

55 2. The construction specified in claim 1 in which the gutter members are provided with grooves into which the edges of the bed member are fitted and the tongues on the ends of the bed members are beveled.

WARREN A. SOMERVILLE.
